VARIABLE DISPLACEMENT GEAR PUMP

Christian E. Grosser, Warwick, R. I., assignor, by
mesne assignments, to Cread Engineering and
Research Company, Cranston, R. I., a corpora-
tion of Rhode Island

Application April 27, 1946, Serial No. 665,440

6 Claims. (Cl. 103—120)

1

This invention relates to variable-displacement hydraulic pumps of the gear-type and consists in improvements in the construction and method of operation thereof.

One object of the invention is to provide a hydraulic gear-pump of simple and compact construction adapted for manufacture at low cost.

Another object is to provide a gear-pump which may be readily adjusted from the outside of its casing to vary the displacement of the fluid discharged therefrom.

Another object is to provide a gear-pump adapted for various uses with its operating parts not subject to excessive wear or deterioration during long periods of use.

Further objects of the improvement are set forth in the following specification which describes a preferred form of construction of the pump, by way of example, as illustrated by the accompanying drawings. In the drawings:

Fig. 1 is an elevational view of the pump shown with a section of its casing removed to disclose the working parts therein;

Fig. 2 is a similar view showing the pump adjusted for a different displacement capacity;

Fig. 3 is a transverse sectional view of the pump taken on line 3—3 of Fig. 1;

Fig. 4 is an enlarged fragmentary view of the ring-gear and the pinion driven therefrom shown in certain relation thereto;

Fig. 5 is a similarly enlarged fragmentary view of the driving pinion shown in mesh with the ring-gear in a relationship corresponding to the relationship of the driven pinion and ring-gear in Fig. 4; and

Fig. 6 is a view similar to Fig. 4, but illustrating a different relationship between the driven pinion and the ring-gear.

The present improved variable-displacement pump comprises, in general, a cylindrical casing or housing 2, a ring-gear 3 and a pair of pinion-gears 4 and 5 arranged with their teeth in mesh with the teeth of the ring-gear.

Referring particularly to Figs. 1 and 3, the cylindrical casing 2 is of relatively narrow width comprising two halves or sections 7 and 8 spaced at a distance apart to provide a substantially circular cavity or chamber surrounded by an annular rim 10. The two sections 7 and 8 are machined on their opposed faces and adapted to be clamped against the opposite machined faces of the annulus or rim 10 to form an enclosure for the gears. A series of bolts 11 extend through the peripheral portions of the sections 7 and 8 and are provided with suitable nuts 12 for draw-

ing the parts together to seat the halves of the casing snugly against the opposite faces of the annulus or rim 10. If desired, gaskets, not herein shown, may be used between the engaging surfaces of the sections 7 and 8 and rim 10 to provide an oil-tight joint for the parts. Certain of the bolts 11 may be employed for attaching the casing to a bracket 15, shown in Figs. 1 and 2, which may be fastened to an upstanding wall or stanchion or in other cases used as a base for the pump in accordance with the position it is to occupy.

The annular insert or rim 10 is provided with two plane faces 16 on the opposite sides of its interior which form parallel ways for a slideable bearing-ring 17 to adapt the latter for eccentric adjustment relative to the axis of the casing. The interior face of the bearing-ring 17 is machined to provide a raceway for a series of friction-reducing elements such as the rollers 20 shown most clearly in Figs. 1 and 3. The bearing-rollers 20 are mounted in a circumferential groove 21 in the periphery of the ring-gear 3 to adapt the latter to turn freely within the bearing-ring 17.

The bearing-ring 17 may be adjusted diametrically across the interior of the casing 2 by any suitable means such as a screw-shaft 22 threaded through the side of the insert or spacing rim 10 and carrying a handwheel 25 or any other suitable manually- or mechanically-operative element. As shown in the present drawings, the screw-shaft 22 is reduced at its inner end and provided with a boss or flange-like head 23 engaged in a slot 24 in the side of the bearing-ring 17 for connecting it to slide the latter. The handwheel 25 may be fitted to the outer reduced end of the screw-shaft 22 and secured rotatively therewith by means of a set-screw 26 and nut 27.

The pinion 4 is constituted as the driving-gear of the pump, being keyed at 29 to a drive-shaft 30 journaled in suitable bearings in the opposite sections 7 and 8 of the casing 2. The drive-shaft 30 may carry a pulley, gear or other power-driven element keyed thereto or it may be connected directly to a motor or other source of power. The driven pinion 5 is mounted free to rotate on a stub-shaft 31 held in bores in the opposite faces of the sections 7 and 8 of the casing 2. The two pinions 4 and 5 are thus journaled in spaced relationship on opposite sides of the transverse axis of the casing with the peripheries of their teeth in close contact with the cylindrical faces 32 and 33 of a separator-element or block 35 secured fast at the center of the chamber. The separator 35

is of substantially I-shape with the circular contact faces 32 and 33 formed by concavities on its opposite sides. The separator 35 may be held fixedly at the center of the casing 2 with its concaved faces 32 and 33 arranged concentrically of the pinions 4 and 5 by means of a pair of pins 36 driven into holes in the section 7 of the casing 2, see Fig. 3.

One of the sections of the casing 2 is provided with suction and discharge openings 40 and 42, respectively, communicating with the interior of the casing 2. The suction opening 40 may be provided with a pipe 41 threaded thereinto and connected with a source of fluid such as oil; and, likewise, the discharge opening 42 may have a pipe 43 threaded thereinto and arranged to feed the oil to a motor or other apparatus to be driven or controlled thereby. When the driving pinion 4 is driven from a suitable source of power connected to its shaft 30 the meshing engagement of its teeth with the teeth of the ring-gear 3 will rotate the latter to drive the pinion 5 through the meshing engagement of its teeth therewith.

Referring to Figs. 4 to 6, inclusive, it will be observed that the teeth on the pinions and ring-gear are of peculiar form, the teeth on both pinions 4 and 5 having a development somewhat like that of ordinary gear-teeth, but more pointed at their ends; while the teeth on the ring-gear 3 have slightly concaved working faces which merge in sharp points at their outer ends. The purpose of this peculiar and novel formation of the teeth will be understood more clearly by the following explanation of the method of operation of the pump. It will be understood by referring to Figs. 1 and 2 that the ring-gear 3 may be adjusted diametrically with respect to the axis of the casing 2 to vary the relationship between its teeth and the teeth of the two pinions 4 and 5; it being obvious that such adjustment of the ring-gear is limited by the bottoming of the teeth of either one of the pinions between the teeth of the ring-gear as indicated at the right in Fig. 1 and at the left in Fig. 2. With the ring-gear 3 adjusted to the position shown in Fig. 1 a relatively large inter-tooth spacing is effected between the teeth of the pinion 4 and those of the ring-gear 3; whereas, the teeth on the pinion 5 will be closely inter-related to the teeth on the ring-gear 3.

Referring to Fig. 1, in the operation of the pump the volume of oil transferred in all instances by means of the inter-tooth spaces at (C) between the teeth of the pinion 4 traveling against the concaved surface 32 is exactly equal to and balanced by the oil transferred at (D) by the teeth of the pinion 5 traveling in the opposite direction against the concaved face 33 of the separator 35. With the ring-gear 3 adjusted to the position shown in Fig. 1 the clearance space between the teeth of the pinion 4 and those of the ring-gear 3 is maximum at (A) and minimum at (B) where the teeth of the pinion 5 mesh closely with the teeth of the ring-gear 3. In this position of the ring-gear the delivery of the pump is equal to the volume of oil entering the suction opening 40 and transferred at (A) minus the oil transferred at (B). Now, if the ring-gear 3 is displaced to the right the clearance space between the teeth of the pinion 4 and those of the ring 3, or at (A), is decreased while the clearance at (B) is increased with a corresponding change in the volume of oil transferred through these spaces. On the other hand, with the ring-gear 3 positioned in concentric relation

with respect to the two pinions, that is, having its teeth in equal engagement with the teeth on both of them, the clearances at (A) and (B) will be equal and no oil will be pumped.

However, as motion of the ring-gear 3 is continued to the right, the clearance between the teeth of the pinion 5 and those of the ring-gear 3, that is at (B), will be increased and the clearance between the teeth of the pinion 4 and those of the ring-gear 3 at (A) decreased to such an extent that the direction of pumping will be reversed when the ring-gear is finally adjusted to the position shown in Fig. 2; the opening 42 thereby becoming the suction inlet for the pump and the opening 42 the discharge outlet.

The present invention provides a pump of exceedingly inexpensive construction wherein the displacement can be varied by infinitely small steps from a maximum in one direction through zero to a maximum in the opposite direction. When the present pump is used for serving power to a hydraulic motor of fixed displacement it becomes a variable-speed hydraulic transmission device similar in operation to multiple piston-type transmissions now in use. Its applications to use for transmission devices of this type are extensive including machine tools, paper-mill equipment, wire-drawing equipment, conveyors and other light apparatus, thereby being adapted to displace conventional multiple piston-pumps of high cost heretofore undesirable where small amounts of power are involved. In other words, the present variable displacement gear-pump provides an inexpensive variable-speed hydraulic transmission device in the small power field where cost is an important factor. Moreover, the simplicity of the present design, besides making for low cost of manufacture, results in a pump of especial compactness and light-weight while reducing wear and deterioration of its parts in comparison to the conventional piston-type pumps heretofore used.

While the present improved pump is herein shown as embodied in a preferred form of construction, it is to be understood that modifications may be made in the structure and arrangement of its parts without departing from the spirit or scope of the invention. Therefore, without limiting myself in this respect, I claim:

1. A variable-displacement gear-pump comprising a casing, a ring-gear rotatable within the interior of the casing, means for adjusting the ring-gear in a direction diametrically of its axis, a pair of pinions journaled in spaced relationship within the casing with their teeth in mesh with the teeth of the ring-gear, a separator held fixedly within the casing between the pinions and provided with concave faces on its opposite sides in contact with the peripheries of the teeth on the two pinions, and suction and discharge openings in the casing located on opposite sides of a line passing through the axes of both of said pinions, said openings being separated from each other at all times by said pinions, said ring-gear and said separator.

2. A variable-displacement gear-pump comprising a casing having an interior chamber, a pair of pinions journaled in spaced relationship within the chamber, a ring-gear surrounding the pinions and formed with internal teeth meshing with the teeth of the pinions, a mounting for rotatably supporting the ring-gear, means for displacing said mounting to adjust the ring-gear relatively of the pinions to cause the teeth of said ring-gear to engage to a greater extent with the

teeth of one pinion and a lesser extent with the teeth of the opposite pinion, a separator positioned between the pinions and provided with concave faces in contact with the peripheries of the teeth of said pinions, and suction and discharge openings communicating with the chamber, said suction and discharge openings being located on opposite sides of a line extending through the axes of both of said pinions, said openings being separated from each other at all times by said pinions, said ring-gear and said separator.

3. A variable-displacement gear-pump comprising a casing having a substantially cylindrical interior chamber, a pair of toothed pinions journaled on opposite sides of the axial center of the chamber in the casing, a separator fixed at the axial center of the chamber and provided with concave faces in contact with the peripheries of the teeth on the pinions, a ring-gear rotatable in the chamber of the casing with its internal teeth in mesh with the teeth of both pinions, means for displacing said ring-gear eccentrically of the axis of the chamber to vary the extent of contact of its teeth with the teeth of the different pinions, and suction and discharge openings in the casing located on opposite sides of a line passing through the axes of both of said pinions, said openings being separated from each other at all times by said pinions, said ring-gear and said separator.

4. A variable-displacement gear-pump comprising a casing having an interior chamber, a pair of pinion-gears journaled in spaced relationship in the chamber, a stationary separator element within the chamber having concave faces in contact with the peripheries of the teeth on the pinions, a bearing slidably mounted within the chamber for displacement in eccentric relation to the pinions, a ring-gear rotatably mounted in said bearing with its internal teeth in engagement with the teeth of both pinions, means for adjusting the bearing to displace the ring-gear in the chamber to vary the extent of engagement of its teeth with the teeth of the two pinions, and suction and discharge openings in the casing located on opposite sides of a line passing through the axes of both of said pinions, said openings being separated from each other at all times by said pinions, said ring-gear and said separators.

5. A variable-displacement gear-pump comprising a casing having an interior chamber with suction and discharge openings communicating

therewith, ways on the opposite walls of the chamber, a bearing slidable on said ways in the chamber, a ring-gear rotatably mounted in said bearing and formed with internal teeth, a pair of pinion-gears journaled in opposite spaced relation within the ring-gear with their teeth in mesh with the teeth of said ring-gear, a separating element fixedly mounted within the chamber and provided with concave faces in contact with the peripheries of the teeth on both pinions, and means on the outside of the casing connected to the bearing for sliding the latter to displace the ring-gear within the chamber to vary the extent of engagement between its teeth and the teeth of both pinions, said suction and discharge openings being located on opposite sides of a line extending through the axes of both of said pinions, said openings being separated from each other at all times by said pinions, said ring-gear and said separator.

6. A variable-displacement gear-pump comprising a casing, a ring-gear rotatable within the casing and formed with internal teeth having concave lateral working faces, a pair of pinions journaled in spaced relationship within the casing and formed with teeth having convex lateral working faces conforming to the shape of the teeth in the ring-gear, the teeth on both pinions meshing with the internal teeth on the ring-gear, a separator fixed within the casing between the pinions and provided with concave faces in contact with the peripheries of the teeth on the two pinions, means for displacing the ring-gear relative to the pinions to vary the extent of engagement and thereby the clearance spaces between the teeth on the pinions and the teeth on the ring-gear, and suction and discharge openings in the casing located on opposite sides of a line passing through the axes of both of said pinions, said openings being separated from each other at all times by said pinions, said ring-gear and said separator.
